W. F. MAHONY

GOLF TEE

Filed Feb. 11, 1924

FIG. 1.

FIG. 2.

FIG. 4.

FIG. 3.

Inventor

William F. Mahony,

By *Cedricus Bryant Derby*
Attorney

UNITED STATES PATENT OFFICE.

WILLIAM F. MAHONY, OF WASHINGTON, DISTRICT OF COLUMBIA.

GOLF TEE.

Application filed February 11, 1924. Serial No. 692,072.

To all whom it may concern:

Be it known that I, WILLIAM F. MAHONY, a citizen of the United States, residing at 1817 Newton St. NW., in the city of Washington, District of Columbia, have invented new and useful Improvements in Golf Tees, of which the following is a specification.

The present invention relates to golf tees and has for its object to produce a tee in which provision is made for tees of varying heights, so as to meet the needs of different players.

In the disclosure herewith, the invention is worked out in different forms, and it will be obvious that other variations can be made without departing from the principle of my invention.

In order that the invention may be clear, I have shown in the accompanying drawings, two embodiments of it, and in said drawings:

Fig. 1 is a plan view of a golf tee mat constructed in accordance with my invention.

Fig. 2 is a side edge view of the mat shown in Fig. 1.

Fig. 3 is an end edge view partly in section of the mat shown in Fig. 1.

Fig. 4 is a view of a modified form of mat.

Referring to the drawings by numbers, like numerals indicating like parts in the several views, 10 indicates a mat of rubber or other suitable material. It may be of any convenient shape and size, and if desired, may be made in two parts as shown in Figs. 1 and 2, and hinged together by suitable links 11 or equivalent devices. The mat 10 should be of suitable weight and thickness to lie snugly upon the tee, and it may, if desired, and as shown in Fig. 3, be embedded in the earth and pinned or otherwise secured by suitable pin members 12, so as to hold it securely in place.

The mat 10 will be provided with a series of tees 13 which will be of varying heights either lengthwise of the mat as shown in Fig. 2, or transversely of the mat as shown in Fig. 3 and it is obvious that the tees may be variously grouped so far as height is concerned, it being understood, however, that there will be one row, for example the

left hand row in Fig. 1, which will be low and of uniform height, while the succeeding rows will be of gradually increasing height to the end of the mat. In Fig. 3, the variation in the heights of the tees will be widthwise of the mat instead of lengthwise thereof, as shown in Fig. 2. It is clear that the groupings and arrangements of tees may be varied as desired. Each tee 13 is sufficiently spaced apart from its adjacent tee to permit it to singly and independently support a ball thereon.

By providing the hinged sections as shown, the mat may be conveniently folded up for handling or storing.

The tees 13 may, and preferably will be, hollow and open through the mat as shown in Fig. 3, so as to provide drainage and prevent water collecting in the hollow tees.

In Fig. 4, a different form of mat is shown.

In the form there shown, the mat is made up of blocks 14, pinned together by suitable fastenings 15, spacer blocks 16 being provided to alternate with the tee blocks. The tee blocks have the tee members 17 projecting therefrom, preferably of different heights, as shown and described in connection with the other views. With this construction, a mat is provided which may be rolled closely for transportation and storage, and one which is adapted by reason of its skeleton arrangement to engage closely the ground or embed itself readily in the earth.

While the purpose of my invention is to arrange in close proximity, tees of varying heights, so as to provide a very considerable number from which to select, it will be apparent the invention is equally adaptable where the tees are of uniform height, and it is desired to provide simply a plurality of tees, any one of which can be used.

Such changes as are within the skill of the mechanic and obvious variations of the construction here shown may be made and still be within the range of my invention.

I claim:

1. A golf tee having a mat portion and a plurality of rows of tees extending across the mat, said tees being spaced apart to permit each tee to support a ball.

2. A golf tee having a mat portion and a

- plurality of rows of tees of different heights extending across the mat.
3. A golf tee having a mat portion and a plurality of rows of tees of gradually increasing heights extending across the mat.
4. A golf tee having a mat portion formed of articulated link members and tees projecting from some of the link members.
5. A golf tee having a mat portion formed of articulated link members, and tees projecting from alternate rows of link members.
6. A golf tee having a mat portion formed of articulated link members and tees of different heights projecting from alternate rows of link members.

In testimony whereof I have hereunto set my hand.

WILLIAM F. MAHONY.
